(57) **CLAIM**

The ornamental design for a fan assembly, as shown and described.

DESCRIPTION

FIG. 1 is a front, bottom perspective view of a fan assembly showing our new design;

FIG. 2 is a top perspective view showing the design for the fan assembly of FIG. 1;

FIG. 3 is a rear elevational view showing the design for the fan assembly of FIG. 1;

FIG. 4 is a bottom plan view showing the design for the fan assembly of FIG. 1; and,

FIG. 5 is top plan view showing the design for the fan assembly of FIG. 1.

In FIGS. 1–5, the broken line showing of various items including (i) the central vertical support member (FIGS. 1–3 and 5), (ii) a portion of the ceiling to which the central vertical support member is attached (FIG. 1), (iii) the features at the top of the motor housing including the raised rim (FIGS. 2, 3, and 5), (iv) the fan blades and associated mounting apparatus including the annular member to which mounting brackets are attached (FIGS. 1–5), and (v) the fastener member located at the lower apex of the fan assembly (FIGS. 1, 3, and 4) is for illustrative purposes only and forms no part of the claimed design.
